UNITED STATES PATENT OFFICE.

THOMAS VILLAGE, OF CROMWELL, CONNECTICUT, ASSIGNOR TO STEVENS & BROWN MANUFACTURING COMPANY, OF SAME PLACE.

DESIGN FOR MATCH-BOX.

Specification forming part of Design No. 6,148, dated September 17, 1872.

To all whom it may concern:

Be it known that I, THOMAS VILLAGE, of Cromwell, in the county of Middlesex and State of Connecticut, have invented a Design for Match-Boxes, of which the following is a specification:

The nature of my design is fully represented in the accompanying photographic illustration, to which reference is made.

A is a shield-shaped plate that forms the back of the box, and is provided with holes *a a* for its attachment by nails to any support. To this shield the body B of the box is attached. The body consists of a shell, formed to repre-

sent a bust of General Ulysses S. Grant with an undress military cap on his head. On the plate A, above the head, is a constellation of stars, and at each side thereof there is a United States flag, and below this a cannon and stack or pile of balls, emblems of war.

What I claim as my invention is—

A design for match-boxes, substantially such as above described.

THOMAS VILLAGE.
